Wm. Nash. Inventor

UNITED STATES PATENT OFFICE.

WILLIAM NASH, OF DENVER, COLORADO, ASSIGNOR TO THE NASH TRACTOR COMPANY, OF DENVER, COLORADO, A CORPORATION OF COLORADO.

AUXILIARY RADIATOR FOR AUTOMOBILES.

1,353,263.

Specification of Letters Patent. Patented Sept. 21, 1920.

Application filed November 13, 1917. Serial No. 201,733.

To all whom it may concern:

Be it known that I, WILLIAM NASH, a citizen of the United States, residing at the city and county of Denver and State of Colorado, have invented certain new and useful Improvements in Auxiliary Radiators for Automobiles; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to radiators for automobiles, especially where they are used for heavy work, such as tractors.

The object is to obtain more rapid cooling, and is attained by the use of an auxiliary radiator.

The invention comprises a tank, constituting an auxiliary radiator, mounted above the engine and having connections with the water jacket and original radiator so arranged that the water passes directly from the water jacket into the tank and from the tank into the original radiator whence it is conducted back to the water jacket.

In the drawings forming a part of this specification,

Figure 1 is a view taken generally on the line 1—1, of Fig. 2, showing the invention in vertical section and the other parts of the power plant in side elevation.

Fig. 2 is a front elevation as indicated by the line 2—2 of Fig. 1.

Fig. 3 is an enlarged detail of the connection used to direct the water from the jacket to the tank and from the tank to the original radiator.

Fig. 4 shows a detail of the coupling.

The original motor 3, with its water jacket 4, and radiator 5 are used. The hood is removed and a tank or auxiliary radiator 7 is mounted on the seats 6 formerly occupied by the hood. The tank may be maintained in place by standards 11 secured thereto and held at their lower ends by the usual means for holding down the hood, or rods may be passed over the tank at each end and secured at their lower ends in the same way as the standards.

The tank 7 by means of the pipes 8 and 9 has connection with the jacket 4 and ra-

diator 5 through the medium of a coupling 10 located between the jacket 4 and the usual flexible connection 12. The coupling 10 is similar to the ordinary coupling at this point except that it has a partition 13 forming chambers 14 and 15 and is provided with openings in its side walls, one communicating with each of the chambers 14 and 15 to receive the pipes 8 and 9 as indicated at 16 and 17 respectively. The upper end of the pipe 8 extends to a point near the top of the tank 7 as indicated at 18 while the pipe 9 merely enters the bottom of the tank. A filling cap 19 is provided on the tank.

When the engine is running the heated water passes from the jacket into the chamber 14 of the coupling 10 and is directed by the partition 13 through the pipe 8 into the cooling tank 7 where it is discharged at point 18, the top of the pipe at this point being approximately even with the water level or slightly above it but not so high that the effect of the heat on the water in the jacket will not cause it to overflow. In this way the hottest water is being continually discharged on the surface of the water at one end of the tank 7. As the water cools, it sinks to the bottom of the tank and the coolest water is drawn therefrom at the other end, passing through the pipe 9 to the radiator 5 where it is further cooled and then passed back to the water jacket.

The invention is designed mainly for use where the machine is in the form of a tractor and the engine heats up rapidly. The tank offers a large cooling space and thereby constitutes a valuable auxiliary radiator. In actual use this structure has furnished ample cooling means where the automobile was used as a tractor in connection with heavy farm work, under which the ordinary radiator was totally incapable of doing the work. The hood being removed and the tank or auxiliary radiator being set above the engine leaves the space underneath the tank open so that further cooling is obtained by passage of the air over and around the engine.

By actual experience it has been found that for some peculiar reason good circulation will not take place unless the partition 13 is perforated. Therefore, a small opening 22 is formed therein. It appears that this is necessary to allow steam and some

water to pass directly to the automobile radiator, while the bulk of the water passes first to the tank. It seems that back pressure of the steam is thus avoided.

5 Obviously it will be necessary to plug the overflow pipe in the original automobile radiator.

What I claim is:

10 1. The combination with the engine and radiator of an automobile, the engine having a water jacket, of an auxiliary radiator comprising a tank, a coupling connected with the upper part of the water jacket and connected with the automobile radiator, said 15 coupling having a partition therein, forming a chamber on each side of said partition, a pipe connection between each of said chambers and the tank, one chamber being in communication with the water jacket and 20 the other in communication with the automobile radiator, said partition having a small opening therethrough.

2. The combination with the engine, water jacket and radiator of an automobile, of an auxiliary radiator comprising a tank, a coupling between the water jacket and the automobile radiator, said coupling having two

separated chambers, each chamber having separate communication with the tank at separated points in the tank.

30

3. A coupling for use with an auxiliary cooling system for automobiles, said coupling having a partition therein forming two chambers, an opening for each chamber in the side of the coupling, an opening 35 in each end of the coupling, and said partition having a small opening therethrough.

4. The combination with the engine and radiator of an automobile, the engine having a water jacket, of an auxiliary radiator comprising a tank, a coupling connected with the upper part of the water jacket and connected with the automobile radiator, said coupling having a partition therein, forming a chamber on each side of said partition, a pipe connection between each of said chambers and the tank, one chamber being in communication with the water jacket and the other in communication with the automobile radiator.

45

40 In testimony whereof I affix my signature.

50

WILLIAM NASH.
